UNITED STATES PATENT OFFICE.

LEO. LEEB, OF ALINGSAES, SWEDEN, ASSIGNOR TO ALFRED LEEB, OF NEW YORK, N. Y.

AIR SPINNING-TOP.

SPECIFICATION forming part of Letters Patent No. 466,172, dated December 29, 1891.

Application filed June 13, 1891. Serial No. 396,200. (No model.)

To all whom it may concern:

Be it known that I, LEO LEEB, a subject of the King of Sweden, residing at Alingsaes, Sweden, have invented a new and Improved 5 Air Spinning-Top, of which the following is a full, clear, and exact description.

The invention relates to toys; and its object is to provide a new and improved air spinning-top which is simple and durable in construction, affords great amusement by enabling the operator to propel a wheel into the air to a considerable height, the wheel revolving in opposite directions in its upward and downward movement.

15 The invention consists of certain parts and details and combinations of the same, as will be hereinafter fully described, and then pointed out in the claims.

Reference is to be had to the accompanying 20 drawings, forming a part of this specification, in which similar letters of reference indicate corresponding parts in all the figures.

Figure 1 is a side elevation of the improvement, with parts in section. Fig. 2 is a sectional side elevation of the same. Fig. 3 is a plan view of the handle, with parts in section; and Fig. 4 is a plan view of the propeller-wheel.

The improved air spinning-top is provided with a handle A, on one end of which is formed 25 a bearing B, containing a central aperture C and formed on top and bottom with two plates D and D', each having a central opening in line with the central opening C. The plates D and D' are preferably made of metal and 30 form the bearing proper for the lower part F' of a shaft F, supporting at its upper end the propeller-wheel G. The latter is formed with a rim G', preferably made of a heavy metal, and propeller-blades G², set at an angle and 35 cut from a single sheet-metal blank, as indicated in Fig. 4, the central part G³ being in the shape of a ring and secured by screws or other means to the upper end of the shaft F. A cap F² fits over the ring G³ and is screwed 40 or otherwise fastened to a projection extending through the ring from the upper end of the shaft, as is plainly illustrated in Fig. 2.

On the shaft F is formed an annular projection or flange F³, adapted to rest on the 45 top surface of the bearing-plate D to prevent the shaft from passing too far into the bear-

ing B. Above the flange F³ the shaft is formed into a drum F⁴, on which is adapted to be wound one end of a string H, the other or outer end being provided with a ring I. 55 The lower end of the shaft F is provided with a conically-shaped tip F⁵, preferably made of a heavy metal, so as to hold the shaft F in a vertical position when the propeller-wheel is projected into the air.

On the lower part F' of the shaft F is formed an annular groove F⁶, adapted to be engaged by a pin J, fitted to slide transversely in the bearing B and secured to the free end of a spring K, fastened to the outside of the bearing B, as is plainly illustrated in Figs. 1 and 3. On the outer surface of the free end of the spring K is formed a knob K', adapted to be pressed on by the operator, so as to move the pin J inwardly, the normal position of the latter being out of engagement with the annular groove F⁶.

The device is used as follows: The operator places the propeller-wheel with the lower part of its shaft into the bearing B, as is illustrated 75 in Figs. 1 and 2, and then winds the end of the cord or string H upon the drum part F⁴. The operator then takes hold of the handle A with one hand and presses on the knob K', so as to move the pin J inward to engage the annular groove F⁶ of the shaft F. The operator then pulls on the ring I, so that the string or cord H unwinds from the drum part F⁴, thereby moving the propeller-wheel. The latter remains with its shaft in the bearing B until 85 the string H is completely off the drum part F⁴, at which time the operator releases the pressure on the knob or button K', so that the spring K moves the pin J outward out of engagement with the groove F⁶. The revolving 90 of the propeller-wheel G causes the wings or propeller-blades G² to act on the air, so that the wheel, on the release of the pin J, flies upward into the air to a considerable height. As soon as the force is spent the wheel drops 95 downward, but by the action of the air on the under side of the wings or propeller-blade G² causes the latter to revolve in the direction opposite to the one it had in its upward movement. Thus it will be seen that the propeller-wheel spins both in its ascent and descent, but in opposite directions. By the operator 100

pulling with considerable force on the string II the wheel may be projected to a considerable height. The weighted tip F⁵ holds the shaft of the wheel in a vertical position in its up and down movements.

Having thus fully described my invention, I claim as new and desire to secure by Letters Patent—

1. The combination, with the wheel having a shaft, of the handle having a bearing for the shaft and a retaining device permanently mounted on the handle for engagement with the said shaft for holding it in the bearing until released by the operator, substantially as set forth.

2. The combination, with the wheel and its shaft having an annular groove, of the handle having a bearing to receive the shaft and a retaining device mounted on the handle and adapted to engage the said annular groove to hold the shaft against outward movement until released by the operator, substantially as set forth.

3. The combination, with the wheel and its shaft provided with an annular groove, of a handle having a bearing for the shaft and a transverse pin mounted on the handle and having a spring normally pressing it outward, the inner end of the pin being adapted to be pressed into said groove by the operator, substantially as set forth.

4. In an air spinning-top, the combination,

with a handle having a bearing formed with a central opening and bearing-plates, of a shaft mounted to turn in the said bearing and having its lower end weighted, the said shaft being formed with a drum part outside of the bearing, a wheel secured on the upper end of the said shaft and formed with a weighted rim and propeller-blades or wings, a string adapted to be wound on the drum part of the said shaft, and a spring-pressed pin fitted to slide in the said bearing and adapted to engage an annular recess in the said shaft, substantially as shown and described.

5. In a flying toy, the wheel having a shaft provided with an annular groove F⁶, a drum F⁴ for the operating-cord above the groove, and a weight F⁵ at its lower end, substantially as set forth:

6. In a flying toy, the handle having a transverse shaft-bearing, a transverse aperture intersecting the said bearing, a pin J in said aperture, and a spring K, secured to the handle and to the pin to press it outward, substantially as set forth.
